DESIGN FOR A TEXTILE FABRIC

Maartem Witsenburg, New York, N. Y., assignor to Lindex Distributors, Inc., New York, N. Y., a corporation of New York

Application February 21, 1947, Serial No. 137,068

Term of patent 3½ years

(Cl. D92—1)

To all whom it may concern:

Be it known that I, Maartem Witsenburg, a citizen of the United States, residing in New York city, county and State of New York, have invented a new, original, and ornamental Design for a Textile Fabric, of which the following is a specification, reference being had to the accompanying drawing, forming part thereof.

In the drawing:

The figure is a plan view of a textile fabric showing my new design.

The design repeats horizontally on the drawing. A design unit is outlined by the solid lines.

I claim:

The ornamental design for a textile fabric, as shown and described.

MAARTEM WITSENBURG.
